T. H. SYMINGTON:
DRAFT RIGGING.
APPLICATION FILED JUNE 30, 1917.

UNITED STATES PATENT OFFICE.

THOMAS H. SYMINGTON, OF BALTIMORE, MARYLAND, ASSIGNOR, BY MESNE ASSIGNMENTS, TO THE T. H. SYMINGTON COMPANY, OF NEW YORK, N. Y., A CORPORATION OF DELAWARE.

DRAFT-RIGGING.

1,378,633.

Specification of Letters Patent. Patented May 17, 1921.

Application filed June 30, 1917. Serial No. 177,930.

To all whom it may concern:

Be it known that I, THOMAS H. SYMINGTON, a citizen of the United States, residing at Baltimore, in the city of Baltimore 5 and State of Maryland, have invented certain new and useful Improvements in Draft-Rigging; and I do hereby declare the following to be a full, clear, and exact description of the invention, such as will enable others skilled in the art to which it appertains to make and use the same.

The invention relates to railway draft rigging, and more particularly to a cheek-plate for use with that type of draft rigging 15 commonly called tandem spring draft rigging. The principal object of the invention is to provide means to greatly strengthen and reinforce, and thereby prolong the life of, a cheek-plate of the type illustrated and described in United States Letters Patent heretofore granted to me on May 26, 1914, 20 No. 1,097,740. The main features of this invention are especially directed to the production of improvements in the cheek-plates 25 described in my former patent, such improvements being designed to accomplish the object heretofore pointed out, while retaining in the new and improved form of cheek-plate the advantages of simplicity of manufacture, low cost of production, and efficiency of design present in the said patented cheek-plate.

There are other features of invention, as will be readily apparent from a more detailed description of the cheek-plate when taken in connection with the accompanying drawings which have been chosen for the purpose of illustrating the device, and in which,

40 Figure 1 is a side elevation of a cheek-plate made in accordance with my invention,

Fig. 2 is a longitudinal horizontal section of the same taken on line 2—2 of Fig. 1, 45 Figs. 3, 4 and 5 are, respectively, vertical sections on lines 3—3, 4—4 and 5—5 of Fig. 1, the directions in which Figs. 3 and 5 are taken being indicated by the arrows adjacent the correspondingly numbered section lines, and

Fig. 6 is a fragmentary top plan view showing the central portion of the improved form of stop casting.

Throughout the specification and claims like parts are designated by like reference characters.

Since the improved form of cheek-plate differs from that illustrated and described in my former patent heretofore mentioned, only in the formation of the main stop shoulders and the upper follower guide flange, it will only be necessary for a complete understanding of this invention to describe the cheek-plate generally except for these particular features.

The cheek-plate comprises a main web or plate 1 having formed thereon upright vertical flanges which constitute the front stop 2, the rear stop 3, and the middle stop 4, the latter preferably comprising a pair of 60 laterally spaced and connected stop shoulders or webs 5 and 6. The portions 7 of the web 1 which extend between the front and middle, and the rear and middle stops, are arranged in a plane parallel to, but 65 spaced inwardly from, the rear wall or sill adjacent face of the casting, so as to form guides for the ends of the follower plates.

A plurality of countersinks or depressions 8 and 9 are provided in each of the portions 7 of the web. The outer, or sill adjacent faces of these countersinks are adapted to contact with the adjacent face of the car sill, and are preferably in the same vertical plane with the outer portions of the web 80 1 at the front and rear portions 10 and 11 of the cheek-plate. The depressions 8 and 9 and the said portions 10 and 11, are suitably apertured as at 12 to receive the securing rivets which connect the cheek-plate to 85 the adjacent sills.

Intermediate the main stop shoulders are also located the front and rear intermediate or limiting stops 13 and 14, respectively. Each of these stops is crossed or intersected 95 by one of the depressions 9.

The upper follower guide flange 15, instead of extending the full width or depth of the middle stop and sloping from the edges or corners thereof to the end stops, 100

as in the patented structure, preferably extends substantially parallel to the back wall of the casting, from the end stops to points 16 which are closely adjacent the middle stop, and then slopes or tapers abruptly toward the inner or yoke-adjacent face of the middle stop. The middle stop 4 is, however, as will be seen from Fig. 6, slightly deeper, or projects laterally farther than the widest portion 15^a of the guide flange 15.

The front stop 2 is provided adjacent the upper and lower portions thereof with forwardly extending lips or flanges 17 and 18 which are preferably made somewhat longer than the correspondingly extending lip or flange 19 which is formed on the intermediate portion of the said stop. These flanges 17, 18 and 19, in conjunction with the inclined bracing webs 20, which are integrally connected thereto, and the main web of the cheek-plate, form longitudinally extending pockets 21 which open on the inner or yoke adjacent face of the cheek-plate. The outer faces of these lips or flanges form an extended bearing against which the adjacent portion of the yoke may rub, and also serve to greatly strengthen and reinforce the vertically extending flange which forms the front stop 2. The middle stop 4 is also greatly strengthened by providing the connecting webs 22 thereof with vertically extending lips or flanges 23 which, in conjunction with the said webs 22, form a series of T shaped flanges, the head of each T forming a portion of the yoke adjacent face of the said stop. I also preferably provide a downwardly extending lip 24 on the inner edge of the flange forming the upper end of the said stop, the vertical face of said lip being preferably in the same plane with the outer faces of the T flanges. These lips or flanges 23, 23 and 24 give to the inner face of the middle stop a large wearing area to counteract the rubbing action of the adjacent portion of the draft yoke, and also greatly strengthen the vertical flanges 5 and 6 which form the follower adjacent faces of the middle stop. The pockets 23^a formed by the flanges 5 and 6, the webs 22 and the main web 1 of the casting open, as will be observed from the drawings, on the inner or yoke adjacent face of the cheek-plate. The inner edge of the rear stop 3 is likewise provided with a lip or flange 25, this flange extending rearwardly, and is integrally connected to the bracing webs 26 and is spaced from the main web of the cheek-plate. The longitudinally extending pockets 27 thus formed by the stop member 3, the flange 25, the bracing webs 26 and the main web 1, also open on the yoke adjacent face of the cheek-plate.

Owing to the constantly increasing use of cast steel yokes in draft rigging, it has become of great importance to increase the

area of the malleable iron cheek-plate at all possible points of contact of the same with the yoke. To increase the wearing area of the cheek-plate and at the same time to retain the highly desirable construction heretofore patented to me has given rise to great difficulty and has been successfully accomplished in the device herein described. It will be readily apparent from the foregoing description that the improved form of cheek-plate presents at all places of contact of the same with the yoke a large surface area, and that this additional area is produced by flanges which add great strength to the casting and which do not in the least interfere with the simple method of casting the cheek-plate or make any change in the form of the casting which would prevent its use in the replacement of the type heretofore patented to me.

Having now described my invention, what I claim and desire to secure by Letters Patent is:

1. A cheek-plate for tandem spring draft rigging comprising a main web, a plurality of end stop members connected thereto, said stop members each involving a flange extending inwardly from said web, a middle stop member connected to said web and involving a pair of spaced inwardly extending flanges connected by spaced webs, and means for reinforcing said end stop members said means comprising longitudinally and vertically extending flanges connected to the inner or yoke adjacent faces of said end stop members, and means for reinforcing said middle stop member comprising vertical longitudinally extending flanges connected to said webs, the vertical faces of said flanges being located in the same plane as the inner or yoke adjacent edges of said stop flanges.

2. A cheek-plate for tandem spring draft rigging comprising a main web, a plurality of stop members extending inwardly therefrom and, respectively, forming the three main follower stops, and a plurality of longitudinally extending flanges spaced inwardly from said main web and respectively reinforcing said stop members, the spaces between said flanges and the main web opening upon the inner face of the cheek-plate.

3. A tandem draft rigging side casting having front, rear, and center main stops, the casting being formed with a web of substantially uniform thickness throughout, said web having upright convolutions therein forming said stops, portions of the web at the center stop of the casting, on the inner face thereof, being omitted whereby to permit coring and at the same time leave a large wearing surface.

4. A side casting for tandem draft rigging having a hollow center stop provided with horizontally extending ribs thereacross, said ribs being provided along their inner edges

with wide, vertically extending flanges forming wide wearing surfaces.

5. A casting for draft riggings having a web of substantially uniform thickness and provided with stop shoulders, one of said stop shoulders having horizontal strengthening ribs on the interior thereof, the inner

edges of said ribs being provided with relatively wide flanges extending vertically, said flanges increasing the strength of said stop 10 and also providing a wide bearing surface for parts of the gear to work against.

In testimony whereof I affix my signature.
THOMAS H. SYMINGTON.
